(57) **CLAIM**

The ornamental design for an accessory for spinning top toy as shown and described.

DESCRIPTION

FIG. 1 is a front elevational view of an accessory for spinning top toy, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, bottom perspective view thereof;

FIG. 9 is a front, right-side, top disassembled perspective view thereof;

FIG. 10 is a rear, left-side, bottom disassembled perspective view thereof;

FIG. 11 is a reference view showing a state of use;

FIG. 12 is a reference view showing a state of use; and,

FIG. 13 is a reference view showing a state of use.

The broken lines depict portions of the design that form no part of the claimed design.
